CLAIM

The ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design;

FIG. 3 is a front view of a third embodiment of a display screen or portion thereof with graphical user interface showing our new design;

FIG. 4 is a front view of a fourth embodiment of a display screen or portion thereof with graphical user interface showing our new design;

FIG. 5 is a front view of a fifth embodiment of a display screen or portion thereof with graphical user interface showing our new design; and,

FIG. 6 is a front view of a sixth embodiment of a display screen or portion thereof with graphical user interface showing our new design.

The outermost broken line illustrates a display screen or portion thereof and form no part of the claimed design. The remaining broken lines, illustrating portions of the graphical user interface, form no part of the claimed design.

1 Claim, 6 Drawing Sheets
